(57) **CLAIM**

The ornamental design for a wipes container, as shown and described.

DESCRIPTION

FIG. 1 is a perspective view of a wipes container showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is top plan view thereof; and,

FIG. 7 is a bottom plan view thereof.

The stippling and hashing represent regions of contrasting texture, and the broken-lines disclosure in the views is understood to represent an unclaimed boundary between claimed and unclaimed surfaces.
